CLAIM

The ornamental design for a lift table, as shown and described.

DESCRIPTION

FIG. 1 is a top, front, right side perspective view of a lift table, showing out new design;

FIG. 2 is a bottom, rear, right side perspective view thereof;

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged partial view of detail 9 taken from FIG. 2.

The broken lines depict environmental subject matter that forms no part of the claimed design.

1 Claim, 9 Drawing Sheets
